UNITED STATES PATENT OFFICE.

MAX EMIL TOBELER, OF DETROIT, MICHIGAN.

SELF-LUBRICATING GUIDE PIN.

Application filed September 2, 1927. Serial No. 217,211.

This invention relates to a self lubricating guide pin, and has for its object to provide, in a manner as hereinafter set forth, a pin of such class constructed and arranged to assure the positive lubrication thereof to prevent cutting of guide or leader pin when operating, thus assuring a positive operation.

Further objects of the invention are to provide, in a manner as hereinafter set forth, a self lubricating guide pin, which is simple in its construction and arrangement; strong, durable, thoroughly efficient in its use, readily assembled, and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations, and modifications can be resorted to which fall within the scope of the claims hereunto appended.

In the drawings wherein like reference characters denote corresponding parts throughout the several views:—

Figure 1 is a fragmentary sectional view of a die showing the adaptation therewith of a self lubricating guide pin, in accordance with this invention.

Figure 2 is a vertical sectional view of the guide pin.

Figure 3 is a section on line 3—3, Figure 2.

Figure 4 is a section on line 4—4, Figure 2.

A self lubricating guide pin, in accordance with this invention, varies in dimensions to be adaptable to the size of the die with which the pin is employed, and referring to the drawings 1 and 2 denote, by way of example, a pair of sections of a die with which is to be associated a self lubricating pin in accordance with this invention.

The pin comprises a body portion 3 of appropriate length and of any suitable contour, and as shown is of circular cross section. The body portion 3 is provided for a portion of its length with a pocket or chamber 4 to contain a body of lubricant 5. The pocket 4 is open at the upper end of the body portion 3, and the wall thereof, at its upper end is threaded, as at 6, and which engages a peripherally threaded plug 7, for closing the mouth of the pocket or entrance to the chamber 5. The bottom of the pocket or chamber 4 is of inverted cone shape, as indicated at 8.

The body 3 is formed with a series of spaced openings or ports 9, which communicate with the pocket or chamber 4, and are disposed on a spiral line or a multiple of spiral lines. 60 The said openings 9 are so arranged whereby certain of them will be positioned diametrically opposed in the body 3. Arranged within the pocket or chamber 4, is a rod of felt or other suitable absorbent material 10, provided intermediate its ends with a oppositely disposed offset portions 11, formed with axially extending openings 12, and each of these latter is adapted to aline with a pair of diametrically opposed openings 9. The 70 set of offset portions 11 are arranged above the transverse median of the rod 10. The diameter of the rod 10 is materially less than diameter of the pocket or chamber 4, and the lower end of the rod 10 conforms to the shape 75 of the bottom 8, as indicated at 13. The diameter of the offset portions 11 is substantially the same as the diameter of the pocket or chamber 4.

Common to a pair of diametrically opposed 80 openings 9 and extending therethrough, is a stick or rim of felt 14, which conforms in contour to the shape of the openings 9 and preferably is of less diameter than the diameter of the rod 10. Each stick of felt 14 is not 85 only seated in a pair of diametrically opposed openings 9, but also in that opening 12, of an offset portion, which is arranged in alinement with a pair of diametrically opposed openings 9. The sticks or pins 14 snugly fit with 90 in the openings 9 and 12 and are flush with the outer periphery of the body 3.

The lubricant 5 is drawn into the rod 10, and is conducted therefrom by the stick or pins 14 for the purpose of lubricating the periphery 95 of the body portion 3, as well as the guide passage 15 into which extends the body portion 3, and by this arrangement a self lubricating guide pin is set up, and which also provides means for lubricating the wall of the 100 guide passage with which the pin associates.

The construction aforesaid set forth provides a positive lubrication to prevent cutting of the guide or leader pin during operation, thus insuring positive action, and therefore it is thought that the many advantages of a self lubricating guide pin, in accordance with this invention, can be readily understood, and although the preferred embodiment of the invention is an illustrated and described, yet it is to be understood that changes 105 in the details of construction can be had which 110

will fall within the scope of the invention as claimed.

What I claim is:—

1. A self lubricating guide pin comprising a body portion formed with a lubricant chamber extending lengthwise thereof and further provided with horizontally disposed openings communicating at their inner ends with said chamber and having their outer ends positioned at the periphery of said body portion, an absorbent element within and extending lengthwise of said chamber, and conducting elements mounted in said openings and extended into said absorbent element, and said absorbent element provided intermediate its ends with offset portions for the reception of said conducting elements.
2. A self lubricating guide pin comprising a body portion formed with a lubricant chamber extending lengthwise thereof and further provided with horizontally disposed openings communicating at their inner ends with said chamber and having their outer ends positioned at the periphery of said body portion, an absorbent element within and extending lengthwise of said chamber, and conducting elements mounted in said openings and extended into said absorbent element, said absorbent element provided intermediate its ends with offset portions for the reception of said conducting elements, and said openings arranged on spiral lines.
3. A self lubricating guide pin comprising a body portion formed with a lubricant chamber extending lengthwise thereof and further provided with horizontally disposed openings communicating at their inner ends with said chamber and having their outer ends positioned at the periphery of said body portion, an absorbent element within and extending lengthwise of said chamber, and conducting elements mounted in said openings and extended into said absorbent element, said absorbent element provided intermediate its ends with offset portions for the reception of said conducting elements, said offset portions abutting the wall of said chamber and the remaining part of said absorbent element being spaced from the wall of said chamber.
4. A self lubricating guide pin comprising a body portion formed with a lubricant chamber extending lengthwise thereof and further provided with horizontally disposed openings communicating at their inner ends with said chamber and having their outer ends po-

sitioned at the periphery of said body portion, an absorbent element within and extending lengthwise of said chamber, and conducting elements mounted in said openings and extended into said absorbent element, said absorbent element provided intermediate its ends with offset portions for the reception of said conducting elements, said offset portions abutting the wall of said chamber, and the remaining part of said absorbent element being spaced from the wall of said chamber, and said openings arranged on spiral lines.

5. A self lubricating guide pin comprising a body portion formed lengthwise thereof with a lubricant chamber and having an inverted cone shaped bottom, said body portion further formed with horizontally disposed openings communicating at their inner ends with said chamber and having their outer ends communicating with the periphery of the body portion, an absorbent element arranged within said chamber and having its lower end conforming in contour to and seated on said bottom, said element of less diameter than the diameter of said chamber and provided intermediate its ends with spaced offset portions abutting the wall of said chamber and opposing the inner ends of said openings, and conducting elements extending through said openings and through said absorbent element at the offset portions thereof.

6. A self lubricating guide pin comprising a body portion formed lengthwise thereof with a lubricant chamber and having an inverted cone-shaped bottom, said body portion further formed with horizontally disposed openings communicating at their inner ends with said chamber and having their outer ends communicating with the periphery of the body portion, an absorbent element arranged within said chamber and having its lower end conforming in contour to and seated on said bottom, said element of less diameter than the diameter of said chamber and provided intermediate its ends with spaced offset portions abutting the wall of said chamber and opposing the inner ends of said openings, and conducting elements extending through said openings and through said absorbent element at the offset portions thereof, said openings arranged on spiral lines.

In testimony whereof I affix my signature hereto.

MAX EMIL TOBELEER.
